METHOD OF TRUING THE PERIPHERAL SURFACES OF BAND SAW WHEELS

Milton H. Mater and Claud C. Walker, Sr.,
Corvallis, Oreg.

Application June 1, 1948, Serial No. 30,444

1 Claim. (Cl. 51—289)

1

Our present invention relates to a method and means for truing the peripheral surfaces of bandsaw wheels or similar rotating bodies such as calender rolls and paper drying rolls. The invention has its greatest utility in truing the surfaces of bandsaw wheels, since a great deal of wear is imposed upon such wheels and the need for true surfaces is acute. Heretofore it has been the practice in bandsaw mills to slow their wheels to approximately one-third of their normal speed while grinding the wheels. In mills driven directly by electric or internal combustion engine power, this is an expensive process, involving the use of separate slow speed motors or engines and/or pulleys and belts; also it involves using many man-hours of skilled millwright labor to install and then dismantle this slowing down set-up. In fact, in the smaller bandsaws used in remanufacturing lumber, it is often the practice to remove the wheels and carry them to a machine shop where they are turned on special machines. The principal object of our invention is to simplify the process of truing up band wheels, so that it is no longer a costly maintenance operation.

Attempts have been made in the past to grind bandsaw wheels running at full speed. These attempts have always been unsatisfactory and highly dangerous because of the high speeds involved, a bandsaw wheel usually operating at peripheral speeds in the range of 9,000 to 10,000 feet per minute. At such speeds a grindstone or grinding block is subject to excess overheating and tremendous pressures, with the result that the grinding member becomes overheated and cannot perform its work, and in various experimental attempts has flown to pieces with resulting injuries to the operator. For these reasons the present practice in bandsaw mills is to shut down the mill and grind the surfaces of the wheels at low speeds. Our invention permits the grinding of the wheels while the wheel is running at high speed.

By previous methods involving slowing the wheels to low speeds, the grinding of the wheel has heretofore required a total elapsed time of from six to twelve hours for a nine-foot wheel, whereas with our invention the total elapsed time for grinding a nine-foot wheel is in the neighborhood of three hours. When it is considered that the wages of skilled millwrights and saw filers are very high and the loss of time of the mill results in much higher losses to the operator, it will be seen that our invention results in a tremendous saving to the mill owner.

The present invention comprises an improvement in shear grinding wherein the surface is

2

trued by a non-motorized rotary grindstone contacting the surface of the wheel along a peripheral edge, with the axis of rotation of the grindstone being inclined to the surface of the wheel. 5 Attempts have been made in the past to shear grind wheels running at full speed by means of a grindstone whose axis of rotation is not only inclined to the surface of the wheel but inclined to the plane of the wheel so that a component of force is imparted to the grindstone, causing it to revolve about its axis. Such attempts have met with failure since the grindstone does not remove metal under these conditions, and more often than not the grindstone flew to pieces. In order 10 to grind the wheel and prevent dangerous destruction of the grindstone, it is necessary to slow the wheel being trued down to approximately 3,000 feet per minute, with the consequent expensive installations, while the mill was shut 15 down so that the bandsaw wheels could be operated at these slow speeds. Attempts have also been made to true wheel surfaces or the like by shear grinding using a rotary grindstone driven by an electric motor at speeds normally encountered in such motors, i. e. in the range of 1,200 to 1,800 R. P. M. Such attempts always fail, since the surface of the wheel is glazed or the 20 grindstone flies apart.

Our invention not only permits of a saving in 25 time, since the total elapsed time is short and the grinding may be accomplished while the wheels are turning at full speed, but also results in a saving due to the lesser wearing of the grindstone resulting therefrom. The best operation 30 known on a nine-foot wheel under previous conditions wore out two complete grinding stones 35 five inches in diameter, whereas when using our invention a single five-inch grindstone will be only about half-worn.

The objects and further advantages of the 40 present invention will be more readily ascertained from inspection of the following specification taken in connection with the accompanying drawings wherein like numerals refer to like parts throughout, while the features of novelty will be 45 more distinctly pointed out in the appended claim.

In the drawings:
Fig. 1 is a view taken from a side of a bandsaw 50 wheel showing a portion of the wheel, and showing the machine of the present invention in operation thereon, portions of the machine being broken away to illustrate details thereof;

Fig. 2 is a plan view of the machine of the 55 present invention;

Fig. 3 is a schematic representation of a band-

saw mill with the machine of the present invention shown in operation on both of the bandsaw wheels;

Fig. 4 is a schematic front view of the lower bandsaw wheel showing the rotary grindstone in one angular relation to the plane of the wheel wherein the peripheral movement of the portion of the grindstone in contact with the wheel is in the direction opposite to the direction of movement of the wheel; and

Fig. 5 is a view similar to Fig. 4 showing the grindstone in a different angular relation wherein the grindstone movement is in the same direction as the movement of the wheel.

A bandsaw mill usually comprises a supporting structure 10 in which is located a pit or well 11. A bandsaw frame 12 is mounted in the pit and supports transverse shafts 13 and 14 forming the axles of the lower bandsaw wheel 15 and the upper bandsaw wheel 16, respectively. A bandsaw 17 is trained about the two wheels and driven at high speed thereby. A carriage 18 is reciprocated alongside of the pit 11 and supports the log 19 with an edge overhanging the pit and in position to be engaged by the bandsaw so that cants and slabs may be sliced from the log. The cant or slab topples onto live rolls (not shown) which transport it from the vicinity of the saw while the carriage is moved back and the log shifted for another cut.

The machine of the present invention comprises a pair of supporting angle bars 25 which are adapted to be mounted horizontally in spaced relation upon the flanges of structural members 26 which may be welded or otherwise affixed to the base of the bandsaw frame at each side of the upper portion of the periphery of the lower band wheel 16, the angle bars being attached by means of bolts 27. A pair of small bracket plates 28 are fixed to the angle bars at each end and support alignment screws 29 engaging the ends of supporting plates 30, each of which supports a pivot bolt 31 or the like. A cradle is pivotally mounted upon the pivot bolt 31, the cradle comprising end plates 32 and longitudinal guiding means such as rods 33. Each of the plates 32 is provided with a limiting pin 34 which projects through an arcuate slot 35 concentric with the axis of the pivot bolts 31 and extending approximately sixty degrees beyond each side of the vertical. A longitudinal traversing screw 37 is rotatably mounted in the plates 32 and fixed to a hand wheel 38 located outside of one of the plates 30. The guide rods 33 pass through guiding lugs 39 depending from a carriage 40 which is provided with a threaded lug 41 threadedly engaging the longitudinal traversing screw 37 whereby rotation of the hand wheel 38 causes movement of the carriage 40 longitudinally of the cradle. The carriage 40 comprises a baseplate having a pair of guide flanges 42 thereon comprising transverse guiding means such as guideways 43. A slide 44 is retained in the guideways 43 and is provided with a threaded depending lug 45 threadedly engaging a transverse feed screw 46 rotatably mounted in lugs 47 on the base of the carriage 40, the screw being provided with a hand wheel 48 whereby rotation of the screw causes transverse movement of the slide 44. A pivot stud 50 projects vertically upward from the slide 44 through an opening in a motor mounting plate 51 supported by the slide 44. An electric motor 52 is mounted upon the motor mounting plate as by means of bolts 53 which do not project below the surface of the motor mounting plate. The motor

52 is preferably of the gear reduction type having a built-in reduction gear box 55 at the forward end thereof from which projects a driven shaft 56. A rotary grindstone 57 is coaxially mounted 5 upon the shaft 56 by any suitable means. The grindstone could be solid, but we prefer the cup type since the shape thereof is conducive to rapid removal of heat from the grinding surface.

The cradle as a whole may be tilted about the 10 pivot bolts 31 until the limiting pin 34 strikes the end of slot 35. The weight of the motor tends to hold the cradle in the tilted position, but we prefer clamping the cradle in this position by tightening the bolts 31 so as to prevent chattering. 15 The hand wheel 48 is rotated until the grindstone 57 contacts the surface of the wheel 15. Thereafter as the peripheral edge of the grindstone wears away the hand wheel 48 is turned by the operator to cause rotation of the transverse feed 20 screw 46 so that a constant pressure is exerted on the surface of the wheel to be trued. As seen in Fig. 3, the machine is so arranged that the axis of revolution of the grindstone 57 is in the prolongation of a chord preferably intersecting 25 a normal radius at about its midpoint so that the end face of the grindstone lies in a plane of about thirty degrees to the surface of the wheel.

The motor mounting plate 51 is held in fixed 30 position relative to the slide 44 by a nut 53 threaded on the stud 50. If the axis of the grindstone is so located as to be parallel to the plane of the wheel, as seen in Fig. 1, the grinding motion will be substantially transverse to the plane of the wheel. If, however, the motor mounting plate 51 is shifted so as to dispose the axis of the grindstone at an inclination to the plane of the wheel, as seen in Fig. 4, the working portion of the edge of the grindstone will be moving in a direction contrary to the direction of movement 40 of the surface of the wheel. If the axis is shifted in the opposite direction, as seen in Fig. 5, the working portion will be moving in the same direction as the surface of the wheel.

In the operation of truing a wheel, we have 45 found that it is necessary to reduce the normal speed of the electric motor, which is generally in the range of 1200 to 1800 R. P. M., to slower speeds so that the peripheral speed of the grindstone would be in the range of 80 to 1100 feet per minute, preferably below 150 feet per minute, such reduction being accomplished through the reduction gearing in the reduction gear head 55. With a bandsaw wheel or a similar rotating member operating at a peripheral speed in the 50 range of 9,000 to 10,000 feet per minute, the ratios of speeds of the wheel surface to the surface of a five-inch grindstone will be in the range of 125 : 1 and 8.2 : 1. The relatively slow rotation of the grindstone causes increments of the working 55 surface of the grindstone constantly to shift from working to non-working position, thus permitting the grindstone to cool itself and causing the fine particles of grit and chips from the wheel to be shaken loose from the pores of the grindstone. The grindstone is moved bodily parallel to the surface of the wheel by turning the hand wheel 38, such movement being controlled by a skilled grinder.

We have found that maintaining the axis of 70 the grindstone parallel to the plane of the wheel, as illustrated in Fig. 1, while rotating the grindstone at a slow relative surface speed with respect to the surface speed of the wheel, will result in efficient rough grinding of the surface. If, however, the axis of the grindstone is angularly

shifted to cause a positive relative movement, as seen in Fig. 4, the grinding action will be accomplished a little faster, and rough grinding is preferably done while the grindstone is so shifted. Shifting the grindstone to produce negative relative movement will reduce the grinding action, and the finer finish grinding is preferably accomplished while the grindstone is so shifted. With a nine-foot bandsaw wheel operating at 10,000 feet per minute and a five-inch grindstone operating at 500 feet per minute, the positive relative grinding movement may be accomplished at speeds in the range of 10,300 to 10,500 feet per minute, when the grindstone is shifted as seen in Fig. 4; and the negative relative speed may be in the order of 9,500 to 9,700 feet per minute when the grindstone is shifted as seen in Fig. 5. The grindstones are very little worn in comparison with previous experience along this line, they are never shattered or exploded, the wheel surface is never glazed, and exact trueness is achieved in a minimum length of time.

In utilizing the grinding mechanism in a bandsaw mill, a vertical shield 60 is built in the space between the upper and lower bandsaw wheels close to the saw to protect the operator from accidentally falling into the saw or moving one of his limbs into the saw accidentally while grinding. The shield 60 may be mounted upon the angle bars 26 and its upper end will support the outer ends of spaced angle bars 61 suitably braced to the frame of the machine to provide a support for the angle bars 25 when the machine is lifted to contact the lower surface of the upper wheel 16. The same principle may be put into operation by canting the cradle until the pins 34 contact the opposite limit of the limiting slot 35. If desired, the cradle may be reversed end for end so that the end face of the grindstone faces the oncoming portion of the upper band wheel, as was the case when the grinding of the lower band wheel is accomplished. However, either direction of movement relative to the grindstone is permissible and permitted by practicing our method and utilizing our machine.

Having illustrated and described a preferred embodiment of the invention, it should be apparent to those skilled in the art that the invention

permits of modification in arrangement and detail. We claim as our invention all such modifications as come within the true spirit and scope of the appended claim.

5 We claim:

The method of truing the peripheral surface of a band saw wheel of large diameter and comprising a rim and radial supporting means secured to portions of said rim with other portions thereof being radially free whereby centrifugal force effects distortion of the peripheral surface of said rim, comprising rotating the wheel to be trued at a high peripheral speed in the order of thousands of feet per minute approximating the peripheral speed of the wheel in use, contacting the distorted portions of the peripheral surface of said wheel with a peripheral edge of a relatively small grinding wheel whose axis of revolution is inclined with respect to the peripheral surface of the wheel at the point of contact and inclined with respect to a plane normal to the axis of the wheel, positively driving said grinding wheel at a relatively low peripheral speed in the order of hundreds of feet per minute, and maintaining the foregoing relative conditions and positions while grinding off the distorted areas of the peripheral surface of the rim during movement of the grinding wheel bodily parallel to the axis of rotation of the wheel whereby to remove surface portions of the rim until the peripheral surface of the wheel to be trued is a true cylinder while rotating at its approximate speed of use.
